PREFORMED NECKTIE

Anthony J. Titone, Corona, N. Y.

Application May 10, 1950, Serial No. 161,160

10 Claims. (Cl. 2—153)

1

This invention relates to neckwear and pertains particularly to a preformed necktie.

One object of the present invention is to provide an improved preformed necktie which simulates the usual four-in-hand necktie but is preferable thereto in that it includes means whereby the breast piece thereof is interchangeable.

Another object of the present invention is to provide the necktie with a preformed tie knot and means whereby a plurality of breast pieces are interchangeably employable with said knot, means whereby the assembled knot and breast piece may be facilitatedly secured about a wearer's neck.

Still another object of the present invention is to provide with a preformed tie knot and a breast piece detachably secured in said knot, means formed integral with said preformed knot and effective for gathering the portion of said breast piece emerging from said knot in a sartorially correct manner.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary front elevational view illustrating one embodiment of the invention.

Fig. 2 is a rear elevational view of the tie knot used in the first embodiment.

Fig. 3 is a plan view.

Fig. 4 is a bottom end view.

Fig. 5 is a sectional view taken along the lines 5—5 in Fig. 2.

Fig. 6 is a front elevational view of the interchangeable breast piece.

Fig. 7 is a perspective view of the neck band.

Fig. 8 is a fragmentary frontal elevation view illustrating a modified form of the present invention.

Fig. 9 is a rear elevational view of the preformed knot used in the modified form seen in Fig. 8.

Fig. 10 is a bottom end view of the Fig. 9.

Fig. 11 is a rear elevational view of a preformed knot in accordance with another modification of the present invention.

Fig. 12 is a side elevational view of Fig. 11.

Fig. 13 is a sectional view taken along the lines 13—13 in Fig. 12 and includes fragmentary il-

2

lustrations of fastening means employable with the second embodiment.

Fig. 14 is a fragmentary isometric view of one of the fastening means used with the form of the invention shown in Figs. 11 to 13.

The necktie, according to the first form of the present invention shown in Figs. 1 to 7, includes a simulated or preformed knot 10 which is suitably formed of plastic or the like. As better seen in Figs. 2, 3, 4 and 5, said preformed knot 10 includes in the rear face thereof a vertical slot having a front wall 11 and outwardly converging side walls 12. Provided in the said front wall 11 adjacent the upper edge thereof is a hook 13 and provided in the side walls 12 are other hooks 14.

Adapted to associate with the first said hook 13 is a hook-eye 15 formed in a stiffening member 16 which is securely stitched in the upper gathered portion of a breast piece 17, seen in Fig. 6. Said stiffening member 16 is configured as to assist in forming the upper portion of said breast piece 17 before it is attached to the preformed knot 10.

It will be seen from comparison of Figs. 3 and 4 that the side walls 12 also converge downwardly. Therefore, the lower portion of said vertical slot is smaller than the upper and this assists in forming the gathered upper portion of the breast piece 17 after it has been attached to the preformed knot 10.

Provided for securing the just described arrangement in the usual tie wearing position is an elastic neck band 18, see Fig. 7. To each extremity of said neck band 18 is secured a hook-eye 19 which is adapted to associate with a respective one of the said other hooks 14 in the side walls 12 of the said preformed knot 10.

It will be seen that the just described embodiment permits selective interchanging of breast pieces and facilitates both said interchanging of breast pieces and the fastening of the arrangement in the usual tie wearing position.

The modification of the invention illustrated in Figs. 8, 9 and 10, is similar to said first embodiment in that it includes a preformed knot 10^a, a vertical slot in the rear face of said knot and having front and side walls 11^a and 12^a, respectively, a first hook 13^a in said front wall for effectively securing a breast piece 17^a to said knot, and other hooks 14^a in said side walls 12^a for associating with fastening means carried on the extremities of a neck band 18^a.

Provided on the said front wall 11^a of the vertical slot in the present knot 10^a, and adjacent

the lower edge of said front wall, is a ridge 20. Said ridge is effective when a breast piece is properly attached to the said knot 10^a for centrally gathering the upper portion of the said breast piece in the sartorially correct manner shown particularly well in Fig. 8.

The further modification of the invention illustrated in Figs. 11, 12, 13 and 14, provides a preformed knot 25 including a vertical slot in the rear face thereof. Said vertical slot provides a front wall 26 whereon is mounted a hook 27 and also divides the rear portion of said knot into two side portions 28.

The said hook 27 is adapted for effectively securing a breast piece 29 in a manner identical to that employed in the above described first embodiment.

Formed in each of the said side portions 28 is a forwardly and outwardly inclined slot 30. As best seen in Figs. 13 and 14 the present embodiment contemplates the provision of an elastic neck band 31 carrying substantially L-shaped hooks 32 on the extremities thereof.

It will be seen that after the breast piece 29 is suitably secured in the knot 25 the said neck band 31 may be fastened to said knot by slidingly passing said L-shaped hooks 32 through the said slots 30, which hooks will effectively engage side walls of said vertical slot and will be thereby effectively retained. This arrangement provides for a facilitated fastening and release of the said neck band 31 and knot 25.

It will be seen further that the ridge 20 of the second modification of the present invention is equally applicable to the just described embodiment and inasmuch as such an application is believed more or less obvious it is not shown or described herein.

It is to be understood that the hooks 14 may be located at any suitable place along or above the side walls 12.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A preformed necktie comprising a knot structure having a vertical slot in the rear face thereof and formed to include a front wall and outwardly converging side walls, a hook mounted on the front wall of said slot, a breast piece having a gathered portion at its top end, a stiffening member included in the gathered portion of said breast piece and having an eye for associating with said hook, a hook mounted in each side wall of said vertical slot, and an elastic neck band having means on each extremity thereof for associating with a respective one of the hooks in said slot side walls.

2. A preformed necktie comprising a solid structure configured to simulate a necktie knot, said solid structure having a vertical undercut slot in the rear face thereof, a hook mounted on the front wall of said slot and adjacent the upper edge thereof, a breast piece having a gathered portion at its top end, a stiffening member included in the gathered portion of said breast piece and having a hook-eye in an exposed end thereof for associating with said hook, a hook mounted in each side wall of said vertical slot,

and an elastic neck band carrying a hook-eye member on each extremity thereof for associating with a respective one of the hooks in said slot side walls.

3. A preformed necktie comprising a solid structure configured to simulate a necktie knot, said solid structure having a vertical slot in the rear face thereof having a front wall and rearwardly and downwardly converging side walls, a hook mounted on the front wall of said slot and adjacent the upper edge thereof, a breast piece having a gathered top portion, a stiffening member included in the upper portion of said breast piece and having a hook-eye in an exposed end thereof for associating with said hook, said stiffening member and said side walls being effective for forming the gathering of the upper portion of said breast piece after the same is secured in said simulated knot, a hook mounted in each side wall of said vertical slot, and an elastic neck band carrying a hook-eye member on each extremity thereof for associating with a respective one of the hooks in said slot side walls.
4. A preformed necktie comprising a solid structure configured to simulate a necktie knot, said solid structure having a vertical undercut slot in the rear face thereof and a ridged portion on the said front wall adjacent the lower edge thereof, a hook mounted on the front wall of said slot and adjacent the upper edge thereof, a breast piece having a gathered top portion, a stiffening member included in the gathered portion of said breast piece and having a hook-eye in an exposed end thereof for associating with said hook to thereby attach said breast piece to said solid structure, said ridge being effective when said breast piece is so attached to assure a proper central gathering thereof, a hook mounted in each side wall of said undercut slot, and an elastic neck band carrying a hook-eye member on each extremity thereof for associating with a respective one of the hooks in said slot side walls.
5. A preformed necktie comprising a solid structure configured to simulate a necktie knot, said solid structure having a vertical slot in the rear face thereof having a front wall and rearwardly and downwardly converging side walls, a hook mounted on the front wall of said slot and adjacent the upper edge thereof, a breast piece having a gathered top portion, a stiffening member included in the upper portion of said breast piece and having a hook-eye in an exposed end thereof for associating with said hook, said stiffening member and said side walls being effective for forming the gathering of the upper portion of said breast piece after the same is secured in said simulated knot, a hook mounted in each side wall of said vertical slot, and an elastic neck band carrying a hook-eye member on each extremity thereof for associating with a respective one of the hooks in said slot side walls.
6. A preformed necktie comprising; a solid structure configured to simulate a necktie knot, said solid structure having a vertical slot in the rear face thereof having a front wall and rearwardly and downwardly converging side walls, and a ridged portion on the said front wall adjacent the lower edge thereof; a hook mounted on the front wall of said slot adjacent the upper edge thereof, a breast piece having a gathered portion at its top end, a stiffening member stitched in the upper portion of said breast piece and having a hook-eye formed in an exposed end thereof for associating with said hook to there-

by attach said breast piece to said solid structure, said side walls being effective for gathering the upper portion of said breast piece and said ridged portion being effective for correctly centralizing the said gathering; a hook mounted in each side wall of said vertical slot; and an elastic neck band carrying a hook-eye member on each extremity thereof for associating with a respective one of the hooks in said slot side walls.

7. A preformed necktie comprising a one-piece knot structure, said knot structure having a vertical slot opening to the rear face and the top and bottom ends thereof, an elastic neckband secured at its ends of said knot structure on opposite sides of said slot, a hook mounted on the material of said knot structure defining the front wall of said slot and closely adjacent the top of said knot structure, a breast piece having a gathered top portion inserted into said slot from the bottom thereof, and a stiffening member mounted in said gathered top portion of said breast piece and having a portion projected from the top of said breast piece, said projected top portion of said stiffening member having an eye engageable by said hook removably mounting said breast piece in position.

8. The preformed necktie as claimed in claim 7 wherein said neckband securement to said knot structure comprises members on the extremities of said neckband, said knot structure having forwardly and outwardly inclined slots extending from opposite sides of said vertical slot and engaged by said members.

9. The preformed necktie as claimed in claim

7 wherein said neckband securement to said knot structure comprises L-shaped hook members on the extremities of said neckband, said knot structure having forwardly and outwardly inclined slots extending from opposite sides of said vertical slot and slidably engaged by said L-shaped hook members.

10. The preformed necktie as claimed in claim 7 wherein said neckband securement to said knot structure comprises elongated members having one of their ends secured to the ends of said neckband, said members having their other ends bent into right angularly extended hook portions, said knot structure having forwardly and outwardly inclined slots extending from opposite sides of said vertical slot and having said elongated members slidably extended therethrough with said hook portions engaging the material of said knot structure at the inner ends of said 15 inclined slots.

ANTHONY J. TITONE.
